FIG. 3.

UNITED STATES PATENT OFFICE.

PER UTNE, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA.

RELAY.

991,117.

Specification of Letters Patent.

Patented May 2, 1911.

Application filed October 19, 1910. Serial No. 587,816.

To all whom it may concern:

Be it known that I, PER UTNE, a subject of the King of Norway, and a resident of the United States, in the borough of Wilkinsburg, county of Allegheny, and State of Pennsylvania, have invented certain new and useful Improvements in Relays, of which the following is a specification.

My invention relates to relays of the electric motor type, the movable part of which is of non-magnetic metallic material and which is caused to rotate by alternating currents flowing in the windings of two oppositely arranged magnets constituting the stationary or field member of the relay.

My invention has particular reference to relays operated by alternating currents which may advantageously be used in signaling systems for railroads, both electric and steam.

A form of electric motor which may advantageously be employed as the operating portion of a relay embodying my invention is shown and described in United States Letters Patent No. 964,714 granted to me on July 19th, 1910.

I will describe a relay embodying my invention, together with its application in a signaling system, and then point out the novel features thereof in claims.

In the accompanying drawings, Figure 1 is a view partly in perspective and partly in diagram of a relay operable by alternating current and embodying my invention. Fig. 2 is a detail view showing a modification of the device controlled by the relay shown in Fig. 1. Fig. 3 is a diagrammatic view showing a portion of an electric railway with a signaling system applied thereto including relays embodying my invention.

Similar reference characters refer to similar parts throughout the several views.

The electric motor portion of a relay embodying my invention has been clearly set forth in the above-mentioned patent. Briefly described, this motor portion comprises a rotating armature D of non-magnetic metal mounted between the faces of two oppositely arranged magnets B and C each having at least two sets of pole-pieces, as for example, b' and c'; and b² and c²; one of the pole

pieces, as b' of one magnet acting in conjunction with the corresponding pole piece c' of the other magnet to produce a turning torque on the armature D in one direction, while at the same time the other pair of corresponding pole pieces, as b², c², neutralize each other and thus produce no turning torque on the armature D. Upon a reversal of the direction of flow of alternating current of the same frequency in the windings of either of the magnets, the relations of the effects of the pole-pieces are so changed that those which first acted to produce a turning torque on the armature now act to neutralize each other, while those which first acted to neutralize each other now co-act to produce a turning torque on the armature, but in an opposite or reverse direction.

In my present invention, I have taken advantage of the reverse rotations of the armature D to perform work. Referring to Fig. 1, I have shown a shaft d, upon which is mounted the armature D, provided with a gear d' which meshes with a segmental gear or rack d² which is suitably pivoted on a base A and has an extension or arm d⁴ which may operate one member of a circuit controller E or other device for opening or closing or varying the resistance, either ohmic or inductive, of an electric circuit, and an arm d⁵ carrying a counterweight. The rotation of the armature in either direction will operate the arm d⁴, though in one direction the counterweight assists the armature in moving the arm d⁴. If desired, therefore, the armature D may operate to move the arm d⁴ to operate the circuit controller to close a circuit, and in so doing raise the counterweight d⁶, so that it tends always to move the arm d⁴ to operate the circuit controller to open the circuit. If, for any reason, alternating current is prevented from flowing in the winding of either of the magnets B or C, there will be no turning torque exerted on the armature D and therefore the counterweight will act to move the armature D in a reverse direction to actuate the circuit controller and cause it to open the circuit. If desired the counterweight may be dispensed with and the segment or rack d² so arranged as to tend, nor-

mally, to move in a direction to open the circuit controller against the action of the armature in moving it to close the circuit controller.

5 In Fig. 2, I have shown the segment or rack d^2 arranged to open a valve d^{10} , controlling the supply of compressed air to a cylinder containing a piston which is suitably connected with some device or part 10 which it is desired to move (as for example a counterweighted signal or trip arm located in a trackway to co-act under some conditions with the braking or power system of cars traveling along a railway). A spring 15 d^{11} acts to always seat the valve to cut off the supply of compressed air from the pipe d^{12} to the cylinder, and the valve is moved against the action of the spring to admit air under the influence of the segment or rack 20 d^2 when moved by the armature D of the motor. It will be seen that the rotation of the armature D in one direction unseats the valve and a rotation in a reverse direction, either under the influence of alternating 25 currents in the magnets B, C, or by gravity, permits the spring d^{11} to seat the valve to shut off the compressed air supply and open the cylinder to the exhaust d^{13} .

The form of relay which I have herein- 30 before described may be used to advantage in signaling systems for railways, where it may act to control a signal circuit, or it may act directly upon movable parts of signaling apparatus, such as semaphore signals, 35 switch-rails, valves for controlling the supply and exhaust of compressed air to cylinders and pistons which in turn are used to move semaphore signals, trip-arms, etc. The rotation of the armature in one direc- 40 tion under the influence of alternating currents in the magnets B and C may be availed of to cause a signal appliance or part to be held in a "clear" or "safety" position, so that if, for any reason, one of the magnets 45 is deprived of current, or alternating current of an opposite polarity should flow in the windings of one of the magnets B, C, and be of sufficient strength, a reverse movement of the armature will result and there- 50 fore the signal appliance or part will be moved or permitted to move to a position to indicate "danger." This application of my invention will be better understood by reference to the diagram of Fig. 3. G designates 55 a portion of an electric railway along which cars are propelled either by an alternating or direct current. If an alternating current is used for the propulsion of cars or trains along the railway, it will, preferably, be of 60 a frequency different from the frequency of the alternating signaling current used in the signaling system. Preferably, the alternating propulsion current will be of a low frequency. I have not shown any transmission

system or generator for the car propulsion current, as these are so well understood in the art as not to require further illustration or description. In such systems it is usual to employ one or both of the track rails of the railway in the return path for the car propulsion current. In Fig. 3 I have shown, diagrammatically, reactance bonds H located at the ends of the block sections and joined by a conductor h for conducting the car propulsion current around insulated joints g 75 placed in the track rails, and thus use both of the track rails in the return circuit for the car propulsion current. The construction of the reactance bonds H which are preferably used are illustrated and described 80 in United States Patent No. 838,916 granted to Louis H. Thullen, on the 18th day of December, 1906.

The railway G is divided into block sections by means of insulated joints g placed in both of the lines of rails. At the entrance end of each block section, a railway signal S, S¹, etc., is located, which may be of any of the well known forms of automatic signals the operation of which is controlled by 90 the passage of cars or trains along the railway in a well known and understood manner. Each block section is provided with a track circuit which comprises a source of signaling current, the opposite track rails 95 of the block section or portions of them, and one or more relay devices. In the drawings, the signaling current is supplied to the track rails of the track circuit by means of trans- 100 formers T, T¹, etc., located about the middle of each block section and having their secondary windings connected with the opposite lines of track rails and their primary winding across feeder mains s s¹—which extend along the line of railway and are connected with an alternating current generator. At each end of the block section I locate a relay device which may conveniently be of the form shown in Fig. 1. The winding of one magnet (either B or C) is connected across the track rails, while the winding of the other magnet is connected with the line conductors s s¹ directly, or through a transformer U having coils of any desired ratio. The armature D of each motor will 110 operate through suitable gearing a movable contact α of a circuit controller, the fixed contact of which is designated α^1 . The contacts α , α^1 of the two relays in each block section are in series circuit and in this circuit there is included some electro-magnetic device of the signal operating mechanism 115 which is well understood in the art. When there is no train or car in any block section, the alternating current flowing in the track 120 rails thereof energizes the windings of the magnets of the relays connected with the track rails, and as the other windings of the

relays are energized from the conductors s^1 the armatures of the relays will be rotated to operate the circuit controllers and close the signaling circuit, thus holding the signal 5 in its "clear" or "safety" position of indication. As soon as a car or train enters a block section the alternating signaling current in the track rails is shunted by the wheels and axles thereof from the winding 10 of the relay which is connected with the track rails of that block section, thus permitting the armature D to be rotated in the reverse direction under the influence of gravity and thus operate the movable contact α of the circuit controller to open the circuit controller and permit the signal to move to "danger" position. This shunting action by the car or train will continue so long as a car or train is in the block section 15 and the winding of either or both of the relays connected with the track rails will be shunted, so that the signal will remain at "danger" position. As soon as the car or train leaves the block section the alternating 20 signaling current again flows through the windings of the magnets of the relay connected with the track rails and the signal will be again moved to indicate "clear" or "safety."

25 The transformers I in adjacent block sections are so connected with the track rails of the block sections that at any one instant the polarity of the signaling current in the rails at the ends of the block sections will be opposite. (This is indicated in the 30 drawings by the usual plus and minus signs). It will be seen, therefore, that the alternating signaling current in the track rails of any one block section has a definite direction of flow, and that the alternating signaling current in the adjacent block section has an opposite direction of flow—so that if, for any reason (as for example the breaking down of one or both of the insulated joints 35 between two adjacent block sections) the signaling current of one block section flows into the track rails of the adjacent block section and into the winding of the relay magnet connected with the track rails of that block section, the direction of flow will be opposite to that of the signaling current 40 in the said block section. If this leakage current is of sufficient strength, it will cause a shifting of the polarity of the ends of the pole pieces adjacent the armature D, in the manner hereinbefore set forth, and will cause a reverse rotation of the armature D to open the signal circuit and therefore permit the railway signal to indicate the 45 dangerous condition of the signaling system.

50 A relay embodying my invention will respond by rotation of its armature D only when both of the magnets are energized by alternating currents of the same frequency.

By reason of the two or more sets of pole 65 pieces of each magnet alternating currents of different frequencies flowing in the coils will have no turning torque on the armature. This will be better understood by a reference to Fig. 1, wherein it will be seen that the 70 copper ferrules on the pole pieces b' b^3 are arranged to produce a turning torque on the armature D in one direction, while the copper ferrules on the pole pieces b^2 b^4 are arranged to produce a turning torque on 75 the armature D in the reverse or opposite direction. As the windings on these pole pieces are in series, it is apparent that any unwarranted alternating current flowing in these windings will have no effect to produce 80 turning torque on the armature D. When therefore a relay embodying my invention as herein described is used on electric railways employing alternating current for car propulsion purposes, the signaling current and the car propulsion current being of different frequencies, even should the alternating car propulsion current flow through the magnet winding connected with the track rails, it would have no effective 85 turning torque on the armature D because it would not be of the same frequency as the alternating signaling current in the opposite magnet winding.

Having thus described my invention, I 95 claim:

1. In an alternating current relay, the combination with a rotatable non-magnetic metal armature, a pair of magnets each having a plurality of pole-pieces arranged on 100 opposite sides of said armature, means comprising a winding for each magnet for causing a co-acting polarization of certain of the pole-pieces of both magnets to produce a turning torque on the armature in one direction upon a flow of alternating current in one direction in said windings and a co-acting polarization of said other pole-pieces of both magnets to produce a turning torque 105 on the armature in a reverse direction upon a change in direction of a flow of alternating current in either of the windings, and means operated upon reverse rotations of the armature for producing mechanical movement.

2. In an alternating current relay, the combination with a rotatable non-magnetic metal armature a pair of magnets each having a plurality of pole-pieces arranged on 110 opposite sides of said armature, means comprising a winding for each magnet for causing a co-acting polarization of certain of the pole-pieces of both magnets to produce a turning torque on the armature in a reverse direction upon a change in direction of a flow of alternating current in either of the windings, and means operated upon reverse rotations of the armature for producing mechanical movement.

115

2. In an alternating current relay, the combination with a rotatable non-magnetic metal armature a pair of magnets each having a plurality of pole-pieces arranged on 120 opposite sides of said armature, means comprising a winding for each magnet for causing a co-acting polarization of certain of the pole-pieces of both magnets to produce a turning torque on the armature in one direction upon a flow of alternating current in one direction in said windings and a co-acting polarization of certain other pole-pieces of both magnets to produce a 125

turning torque on the armature in a reverse direction upon a change in direction of flow of alternating current in either of the windings, a pinion secured to said armature, a rack engaging said pinion and operated thereby, and a circuit controller operated by said rack.

In testimony whereof, I have signed my name to this specification, in the presence of two subscribing witnesses.

PER UTNE.
